(57) CLAIM

The ornamental design for a bag as shown and described.

DESCRIPTION

FIG. 1 is a rear perspective view of a bag showing my new design;

FIG. 2 is an opposite side rear perspective view thereof;

FIG. 3 is a top view thereof; and,

FIG. 4 is an enlarged view of region 4 identified in FIG. 3. The broken line showing of the small circular regions on each clasp forms no part of the claimed design. The broken lines immediately adjacent to the shaded area define the bounds of the claimed design and form no part thereof. The broken lines depicting the remainder of the equipment form no part of the claimed design.
